UNITED STATES PATENT OFFICE,

MADISON BOWMAN AND JOHN BOWMAN, OF TOLEDO, ILLINOIS, ASSIGNORS
OF ONE-THIRD TO R. C. WILLIS, OF SAME PLACE.

THRESHING-MACHINE.

SPECIFICATION forming part of Letters Patent No. 635,742, dated October 31, 1899.

Application filed May 5, 1898. Serial No. 679,784. (No model.)

To all whom it may concern:

Be it known that we, MADISON BOWMAN and JOHN BOWMAN, citizens of the United States, residing at Toledo, in the county of 5 Cumberland and State of Illinois, have invented a new and useful Threshing-Machine, of which the following is a specification.

Our invention relates to threshing-machines, and the improvements are more especially directed to devices by which small 10 seeds, such as timothy and clover, may be cleaned ready for the market without subsequent treatment.

Threshing-machines of ordinary construction embrace as one of the riddles a chaffing screen or board which is arranged in the plane of the lower machine-conveyer and is adapted to deliver to another riddle; but it is found that the chaff and short straw lodge on this 20 screen or board to such an extent as to clog the perforations therein, so that ordinary chaffers not only fail to clean the seed from the chaff, but the blast carries off much of the seed upon the straw-pile. Our invention 25 overcomes these defects by cleaning the seed from the chaff in its travel from the conveyer to the chaffer, and the grain emerges from the machine in a clean condition ready to be placed on the market.

30 Our improvements are readily applied to ordinary threshing-machines at small expense for the purpose of enabling the machine to clean timothy and clover seed from the chaff and straw, and the improvements are detachably but rigidly held in the machine, so that 35 they may be removed when desired to use the machine for threshing and cleaning wheat, oats, and rye.

With these ends in view our invention consists in the novel combination of elements 40 and in the construction and arrangement of parts, which will be hereinafter fully described and claimed.

To enable others to understand the invention, we have illustrated the preferred embodiment of the same in the accompanying drawings, forming a part of this specification, and in which—

50 Figure 1 is a sectional perspective view of part of an ordinary threshing-machine with our improvements applied thereto. Fig. 2 is

a detail perspective view of the screen which is to be placed between one of the machine-conveyers and the chaffing-screen. Fig. 3 is a detail perspective view of an ordinary chaffing-screen with the fastening means for our improved screen thereon. Fig. 4 is a detail perspective view of a conveyer-screen.

Like numerals of reference denote like and corresponding parts in each of the several 60 figures of the drawings.

In order that others skilled in the art may understand our improvement, we have illustrated a part of an ordinary threshing-machine by Fig. 1 of the drawings, in which the 65 numeral 1 indicates a part of the machine-casing. 2 is an ordinary slatted and stepped conveyer therein; 3, the ordinary chaffing-screen; 4, one of the riddles; 5, the conveyer-trough; 6, the screw conveyer therein, and 7 70 the blast-fan. All these parts are ordinary and familiar to those skilled in the art, and to embody our improvements in a machine of this type it is necessary to make a very slight change, which may readily be effected. 75

In ordinary threshing-machines the chaffing-screen or riddle 3 lies substantially flush with the surface of the stepped conveyer 2; but to embody our invention in such threshing-machine we find it necessary to drop the 80 chaffing-screen 3 on a plane below the upper surface of the stepped conveyer, the chaffing-screen being lowered approximately one inch, more or less, according to the thickness of the screen which we employ. This depression 85 of the chaffing-screen 3 provides a seat in the machine-frame 1 above the chaffing-screen, which seat is indicated at 8 in the drawings.

90 9 designates our improved screen, which is suitably attached to a carrying-frame 10, and this screen and its frame are arranged immediately over the chaffing-screen 3 to occupy a horizontal position substantially flush with the upper surface of the stepped conveyer 2. 95 The screen 9 may be of any suitable material, although we prefer to employ a wire fabric the meshes of which provide interstices or openings of such size as to enable small timothy and clover seeds to pass freely therethrough, but the chaff, straw, and refuse is retained on this screen to be blown by the 100

blast from the fan out through the delivery end of the machine.

The screen-frame 10 is constructed so that it may be held detachably but firmly in place 5 on the chaffing-screen 3, and in one embodiment of our invention we provide this frame 10 with the vertical notches 11 in opposite rails of the frame, while in the lower edge of said side rails of the frame are formed the 10 diagonal notches 12.

The chaffing-screen 3 carries the short vertical blocks 13, which are adapted to fit in the vertical notches 11 of the screen-frame, and said screen 3 is furthermore provided on its 15 upper face with diagonal blocks 14. These diagonal blocks or retainers do not extend above the chaffing-screen as high as the vertical blocks 13, and said blocks 14 are thus adapted to fit snugly in the diagonal notches 20 12 of the screen-frame.

The screen 9 is coextensive in area to that of the chaffing-screen, over which it is placed so as to entirely cover the chaffing-screen, and said screen 9 is held firmly and securely 25 in place by the locking blocks or retainers 13 14, which fit in the notches of the screen-frame and are attached to the chaffing-screen. These retainers or blocks hold the screen 9 in position over the chaffing-screen against edge- 30 wise movement in a direction either longitudinally or transversely of the machine-casing 1, and to prevent the screen 9 from vertical displacement in an upward direction the fasteners 15 are attached to the heel or rear end of 35 the stepped conveyer 2, said fasteners extending rearwardly beyond the stepped conveyer and fitting upon one of the end rails of screen-frame 10.

Between the tail end of the riddle 4 and the 40 vertically-movable gate 16 at the rear end of the threshing-machine is formed a seat 17, which lies in a horizontal plane of the riddle 4 and over the conveyer-trough 5, and in this seat 17 is snugly fitted a small screen 18, 45 which is attached to a frame adapted to snugly occupy the space or seat bounded by the walls of the machine-casing, the rear end of the riddle 4, and the vertically-movable gate of the machine. This small screen 18 lies im- 50 mediately over the conveyer-trough, so as to prevent the straw and chaff from lodging therein and allow the timothy and clover seed which may be blown over the screen 9 to pass through said screen 18 and be caught by 55 the conveyer-trough. This small screen 18 has its mesh corresponding to that of the screen 9, and the screen-frame is held in place by suitable fasteners 19 for the purpose of

preventing movement of the screen 18 and allowing the same to be readily removed. 60

When it is desired to use the machine for threshing grain to obtain clover or timothy seed, the screens 9 and 18 are readjusted in place over the chaffer and the conveyer-trough, respectively, and said screens are suitably 65 held in firm relation to the working parts of the threshing-machine. The small timothy or clover seed are free to pass through the screens 9 and 18 to the riddle 4 and the conveyer-trough, while the chaff and straw are 70 carried by the blast out through the delivery end of the machine. For threshing wheat, oats, and rye it is necessary to remove the screens 9 and 18, and the machine may then 75 be used in the ordinary way, because the depression of the chaffer 3 below the stepped conveyer has no appreciable effect on the grain or its treatment.

It is evident that changes in the form and proportion of parts may be made by a skilled 80 mechanic without departing from the spirit or sacrificing the advantages of the invention.

Having thus described the invention, what we claim is—

1. In a threshing-machine, the combination 85 with a stepped conveyer and a chaffing-screen below the working surface thereof, of a fine screen, 9, having its frame seated upon the chaffing-screen and provided with the vertical and diagonal notches, the vertical and diagonal retainers attached to the chaffing-screen, and fitting in the notches of the screen-frame, and fasteners to hold the screen, 9, against displacement, substantially as described.

2. In a threshing-machine, the combination 95 with a stepped conveyer, a chaffing-screen arranged contiguous to and in a plane below the irregular surface of the conveyer, a riddle, 4, and a screw-conveyer casing in rear of said riddle, of the fine screen, 9, coextensive in area to the chaffing-screen and having interlocking connection therewith to lie flush with the irregular surface of the conveyer, another fine screen directly over the screw-conveyer casing and in line with the riddle, 100 and fasteners for detachably securing the fine screens to the riddle and the chaffing-screen, respectively, substantially as described.

In testimony that we claim the foregoing as our own we have hereto affixed our signatures 110 in the presence of two witnesses.

MADISON BOWMAN.
JOHN BOWMAN.
